(57) CLAIM

The ornamental design for a garment, as shown and described.

DESCRIPTION

FIG. 1 is a front view of a garment showing my design;

FIG. 2 is a first side view thereof;

FIG. 3 is a second side view thereof; and,

FIG. 4 is a front perspective view thereof.

The long-and-short broken lines define the bounds of the claim and form no part thereof. The even-length broken lines depict portions of the garment that form no part of the claimed design.
